[57] CLAIM

The ornamental design for a pumpkin scoop, as shown and described.

DESCRIPTION

FIG. 1 is a front perspective view of a pumpkin scoop showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of a second embodiment of that shown in FIG. 1;

FIG. 9 is a front elevational view of that shown in FIG. 8;

FIG. 10 is a rear elevational view of that shown in FIG. 8;

FIG. 11 is a right side elevational view of that shown in FIG. 8;

FIG. 12 is a left side elevational view of that shown in FIG. 8;

FIG. 13 is a top plan view of that shown in FIG. 8;

FIG. 14 is a bottom plan view of that shown in FIG. 8;

FIG. 15 is a cross-sectional view taken along line 15—15 of FIG. 1; and

FIG. 16 is cross-sectional view taken along line 16—16 of FIG. 8.
